Primary Examiner — Robert M Spear*Assistant Examiner* — Ryan Harvey(74) Attorney, Agent, or Firm — Matthew J. Lattig; Charter IP, LLC(57) CLAIM

The ornamental design for a yoga block, as shown and described.

DESCRIPTION

FIG. 1 is a perspective view of a yoga block showing my new design.

FIG. 2 is a front view thereof, the rear view being a mirror-image of the front view and hence not depicted.

FIG. 3 is a left side view thereof, the right side view being a mirror-image of the left side view and hence not depicted; and,

FIG. 4 is a top view thereof, the bottom view being a mirror-image of the top view and hence not depicted.
